(57) **CLAIM**

The ornamental design for a golf swing indicator, as shown and described.

DESCRIPTION

FIG. 1 is a front-right perspective view of a golf swing indicator showing the new design;

FIG. 2 is an additional front-right perspective view thereof, shown as-installed on a golf glove;

FIG. 3 is a front view thereof;

FIG. 4 is a back view thereof;

FIG. 5 is a left view thereof;

FIG. 6 is a right view thereof;

FIG. 7 is a front view showing the golf swing indicator in use;

FIG. 8 is a back view showing the golf swing indicator in use; and,

FIG. 9 is a back-left perspective view showing the golf swing indicator in use.

The broken lines shown represent unclaimed subject matter and form no part of the claimed design.

1 Claim, 8 Drawing Sheets
